FIG. 1 is a perspective view of an invertible pencil and clip holder for a telephone switchboard or the like showing our new design;

FIG. 2 is a perspective view thereof in inverted position;

FIG. 3 is a top plan view thereof;

FIG. 4 is a bottom plan view thereof;

FIG. 5 is an end elevational view thereof;

FIG. 6 is a front elevational view thereof; and

FIG. 7 is a rear elevational view thereof.

The broken line representation of a pencil and a clip in FIG. 1 is for purposes of illustration only and the center of FIGS. 3, 4 and 7 have been broken away for convenience of illustration only.

We claim:

The ornamental design for an invertible pencil and clip holder for a telephone switchboard or the like, as shown and described.
